UNITED STATES PATENT OFFICE.

RUFUS D. WADLEIGH, OF OLD TOWN, MAINE.

BAFFLE BLOCK AND COMBUSTION-CHAMBER TOP.

Application filed April 30, 1921. Serial No. 465,714.

To all whom it may concern:

Be it known that I, RUFUS D. WADLEIGH, a citizen of the United States, residing at Old Town, in the county of Penobscot and 5 State of Maine, have invented certain new and useful Improvements in Baffle Blocks and Combustion-Chamber Tops, of which the following is a specification.

My device consists of an improved baffle-block for use with horizontal tubular boilers and is fully illustrated in the accompanying drawings in which—

Figure 1 is a plan showing a plurality of fire bricks secured in a metal frame and 15 bound together by the frame and transverse bolts.

Figure 2 is a sectional elevation of the device of Fig. 1 looking in the direction of the transverse bolts.

20 Figure 3 is an end elevation.

Figure 4 is an isometric view showing a boiler-head and my device suspended and placed as in actual use.

Similar letters refer to corresponding 25 parts throughout the figures.

In the operation of horizontal tubular boilers the flame and gases under the boiler pass forward to a combustion chamber beyond the boiler head and are deflected backward through the boiler tubes. To resist the intense heat the combustion chamber is formed of solid walls of fire brick or other material, as nearly non-combustible as possible, and is made as permanent as practicable, but nevertheless is rapidly destroyed 35 and requires frequent renewals, which means drawing the fire and a long delay.

My device is a detachable, removable top to the combustion chamber. It can be removed and another substituted in a few moments without drawing the fire in the furnace and thus a great saving in time is accomplished.

I provide a metal frame, preferably rectangular, and formed of thin flat strips of iron plainly shown in Fig. 1 at A, and held together by transverse bolts B. In this frame are fitted rectangular fire-clay bricks C the ends of which are slotted transversely 45 to receive and fit one half of the thickness of the transverse bolts B, as shown in Fig. 2, and the bricks are thus held in position and prevented from dropping. If the bolts are $\frac{3}{8}$ of an inch in diameter the slots in the 55 bricks would be $\frac{3}{8}$ of an inch deep.

Before fitted in the frame the brick are

dipped in liquid clay and when fitted their tops are covered with $\frac{3}{8}$ of an inch of asbestos and the whole is tightly bound together by turning up nuts upon the ends of the transverse bolts, B.

This, the starting point of my device, I call a block, indicated throughout the figures by D and of course it may be made of any convenient size, but I prefer to use a number of small blocks secured together in a frame forming a group or battery as shown in Fig. 4, rather than one of larger size.

Each block or battery D is suspended by a hanger E depending from a truss F resting 70 on pillars GG rising about 16 inches above the walls of the boiler-setting and so placed as to bring one end of the battery D flush against the boiler head, and the hangers E engage with eye-bolts H connected with the 75 transverse bolts B. The other end of the battery is supported upon a ledge upon the rear wall of the combustion chamber.

When one or more of the bricks C forming a block D is so eroded as to be no longer 80 fit for use, the battery is raised slightly and moved back from the boiler toward the rear wall of the setting, the asbestos packing is picked out or knocked out, the block disengaged from its hanger and removed, and a 85 new block substituted, and the battery is replaced in position against the boiler head.

Any suitable non-combustible material may be used in place of fire brick.

By this form of construction, when a 90 brick C is eroded it may be removed from its block D by chipping the portion of the brick above the slot formed to receive the bolt B securing it in the block, and hammering the brick down and out of the block, and similarly a new brick may be substituted by chipping off the portion of the new brick below the slot which receives the bolt, thus leaving a shoulder which rests upon the bolt when the new brick is hammered down 100 to place. As the blocks may be formed of any convenient size and weight it is obvious that the removal of a block may be easily accomplished as also the removal of one or more of the eroded bricks and the 105 substitution of new bricks, resulting in a great saving of time and expense.

I claim and desire to secure by Letters Patent—

1. A baffle block consisting of the combination of a frame; a plurality of non-combustible brick, each having a transverse slot

upon one of its faces; bolts passing through said slots and the sides of said frame; and means of detachably hanging said blocks to an over-head support.

5. 2. The combination of a horizontal tubular boiler; the boiler furnace; a combustion-chamber; and a baffle-block consisting of a frame, a plurality of non-combustible brick, each having a transverse slot upon one of

its faces, bolts passing through said slots ¹⁰ and the sides of said frame, and means of detachably hanging said blocks to an over-head support.

RUFUS D. WADLEIGH.

In presence of—

HARRIS J. MILLIKEN,
FRED'K A. PATTERSON.
